UNITED STATES PATENT OFFICE.

HOWARD C. CARMICHAEL, OF INDIANAPOLIS, INDIANA.

RAILWAY-CROSSING GATE AND SIGNAL.

Application filed September 10, 1921. Serial No. 499,793.

To all whom it may concern:

Be it known that I, HOWARD C. CARMICHAEL, a citizen of the United States, residing at Indianapolis, in the county of Marion and State of Indiana, have invented a new and useful Railway-Crossing Gate and Signal, of which the following is a specification, reference being had to the accompanying drawings and to the letters and figures of reference marked thereon.

This invention relates to the protection of operators and drivers of vehicles and also pedestrians where railway tracks and highways or streets cross, the invention having reference more particularly to train-controlled means for warning and obstructing those on the roads or streets approaching the crossing, when trains are expected to pass over the crossing.

An object of the invention is to provide an efficient and reliable railway crossing gate and signal which shall be so constructed as to be electrically operated and controlled and permit moving trains, locomotives or cars to control the periods of operation thereof, the aim primarily being to afford protection against loss of life or injury to those who must use railway crossings, and to prevent destruction or damage of motor vehicles and also horse-drawn vehicles.

Another object is to provide apparatus of the above-mentioned character, which shall be of substantial construction and not be liable to derangement in use or in periods between operations, and which shall not be costly for installation and operation.

A further object is to provide an improved safety gate and signal for railway crossings which shall be adapted for obstructing passage across the railway track, and for giving timely signal and warning preceding the crossing of the highway or street by railway rolling stock.

A still further object is to provide a safety railway crossing gate that shall be so constructed as to be adapted to be used where switching is done on railways, to permit a car or train to open the safety gate in case the car or train approaches and causes the gate to be closed and does not pass over the crossing, but stops and returns or moves back from the crossing, so that the crossing may be safely used without delay.

With the above-mentioned and other objects in view, the invention consists in an improved safety crossing gate and novel means for electrically operating and controlling the gate, a novel means for efficiently producing danger signals preceding and during operation of the gate, and in improved means for controlling the periods of operation of the gate and the signals; and, the invention consists also further in the parts and combinations and arrangements of parts as hereinafter particularly described and further defined in the accompanying claims.

Referring to the drawings,—Figure 1 is a sectional elevation of a railway track with which a highway or street crossing is illustrated, and the improved safety gate and signal apparatus associated therewith; Fig. 2 is a top plan of the railway track and crossing in connection with which a series of safety gates and signals are illustrated, together with a diagrammatic illustration of the electrical and mechanical control system embraced in the invention; Fig. 3 is a fragmentary sectional elevation showing more particularly the mechanical control apparatus whereby the periods of operation of the safety gates and signals are controlled by trains or cars moving on the railway tracks; Fig. 4 is a top plan of Fig. 3, parts being in horizontal central section; Fig. 5 is a fragmentary section on the line V—V in Fig. 3; Fig. 6 is a vertical central section of the housing supporting the safety gate and operating apparatus thereof; Fig. 7 is a fragmentary section approximately on the line VII—VII in Fig. 6; Fig. 8 is a fragmentary vertical section of the housing and apparatus therein and a diagrammatic illustration of the electrical system whereby the safety gate is operated and controlled, the safety gate being indicated as in operative position to close the crossing to vehicles and pedestrians; Fig. 9 is a section and diagram similar to Fig. 8 but with the safety gates arranged in inoperative or open position and other parts in different positions relatively to those in the preceding figure; Fig. 10 is an illustration of a reversing and cut-out switch preferably used in the electrical system, and on an enlarged scale and in more detail than appearing in Figs. 8 and 9; and, Fig. 11 is a sectional detail on an enlarged scale.

of an electrical interrupter whereby to automatically cause intermittent flashing or display of signal lights on the safety gates.

Similar reference characters in the different figures of the drawings indicate corresponding or like elements or features of construction herein referred to in detail.

In the drawings, a section of the railway track sufficient to an understanding of the invention is shown in which cross-ties 1 are laid on a suitable road-bed and support two track rails 2 and 3, the numeral 4 indicating the foundation and position of a highway or street crossing the railway track, the numeral 4' indicating the crown of the highway beyond the railway track.

A practical embodiment of the invention includes a suitable upright housing 5 which may be suitably supported firmly adjacent to one side of the railway track and the highway, and in some cases other similar housings 6, 7 and 7' may be arranged as indicated on opposite sides of the railway and highway or street. In some cases, as will be understood, a side-walk or foot-path may be present along the sides of the highway or street. Each housing has a pivot 8 movably supporting a safety gate or arm 9 of suitable length which preferably has a lamp box 10 on its end, the lamp box preferably having glass sides 11 which may be of any desired color or tint. The lamp box is provided with an electric lamp socket 12 to support an incandescent electric lamp 13. The wall of the housing has a slot 14 through which the arm 9 extends, and the arm has a weight or relatively heavy counter-balancing portion 15 within the housing, which preferably is bifurcated. When a side-walk is present the housing is provided also with a pivot 16 opposite to and parallel with the pivot 8 and it supports a small gate or arm 17 which has a counter-weight 18 which preferably is bifurcated, the arm extending through a slot 19 in the housing. For synchronously operating and controlling the gate arms two links 20 and 21 are pivotally connected to the counter-weight portions of the arms respectively and extend downwardly, the links being pivotally connected to a crosshead 22 which may be variously operated and controlled. Preferably the crosshead is loosely arranged on a guide rod 23 so as to slide thereon, and the rod is guided in a suitable hollow guide 24 supported by the top of the housing and extending downward. The rod has a collar 25 thereon designed to be brought into engagement with the crosshead, and the lower end of the rod has a jaw 26 thereon which is arranged below the crosshead and operates as a collar to engage and push up the crosshead.

The safety gate preferably is operated and controlled by means of positive gearing,

in which case the interior of the housing 5 is provided with a support 27 having a stub axle 28 thereon which rotatably supports a gear wheel or segment 29 provided with a crank pin 30 to which a connecting rod 31 is connected, the connecting rod being pivoted to the jaw 26. An electric motor 32, adapted to be reversed in operation, is supported in the housing and has a drive shaft 33 that is steadied in a journal box 34 in the housing, and a worm 35 is fixed on the shaft and in engagement with the wheel or segment 29. This insures steady movement of the safety gate and positive control thereof which is preferred, but it is obvious that in some cases the crosshead 22, or a simple modification thereof, might be operated and controlled by means of a governed solenoid if desired.

The electrical control system through the means of which the motor is actuated and controlled includes two electrical relays 36 and 37 which are alike but differently connected, and designated for descriptive purposes and illustrated outside of the housing 5 merely in the interest of clearness and symbolically, each relay being of well known or any suitable construction and having an armature rod 38, on one end of one of which is a switch bar 39 and a similar switch bar 39' on the end of the other rod. The switch bar 39 is located adjacent to contact devices 40 and 41 suitably supported, and the switch bar 39' is arranged adjacent to similar contact devices 42 and 43. Each relay is suitably timed, being preferably provided with a dash pot comprising a cylinder 44 into which the armature rod extends, the rod having a piston 45 thereon adapted to retard the spring-actuated opening movement of the armature and the switch bar.

Within the housing 5 a suitable reversing and cut-out switch is arranged and preferably is such as illustrated, more clearly in Fig. 10, the switch structure comprising two anchor bars 46 and 47 secured to the wall 5 or lining plate 5' thereof and extends therefrom preferably divergently each from the other, the bars suitably supporting a number of contact points 48 and 49 respectively adapted to have circuit wires connected thereto, there being pivot ears 50 and 51 supported between the bars and adjacent thereto respectively, to which insulating switch bars 52 and 53 are respectively pivoted. One switch bar has two contact plates 54 and 55 thereon arranged to make contact with the contact points 48 in groups, the switch bar 53 having contact plates 56 and 57 thereon to be moved to or from the contact points 49 in groups. The crosshead 22 has a lug 58 fixed thereon and so arranged as to move between the switch bars 52 and 53 when the gate 9 is operated and to alternate-

ly engage and move the switch bars which are connected together by means of a tie rod 59 to which a spring 60 is connected, the spring being suitably anchored and adapted to draw the switch bars to the contact points when moved nearly thereto by the lug.

Any convenient source of electricity may be utilized whereby to operate and control the gates, a battery 61 being symbolically indicated for descriptive purposes. A feed wire 62 and a return wire 63 are connected with the battery or electrical source, and one end of each of the relay coils 36 and 37 is connected with the return wire. The feed wire 62 extends to a contact device (92) in each of the cylinders (89) of several circuit closers. A circuit wire 64 is connected with the opposite end of the coil of the relay 36 and also with the contact device (93) in two of the cylinders (89) embraced in the circuit closing apparatus A and A' which are located at considerable distance from the crossing. A circuit wire 65 is connected with the opposite end of the coil of the relay 37 and also with the remaining one of the contact devices of the circuit closing apparatus B and B' which are located a short distance from the crossing. A circuit wire 66 is connected with the contact device 41 and also with one of the contact points 49. A circuit wire 67 is connected with another one of the contact points 49 and also with a circuit wire 68 connected with the motor 32. Another circuit wire 69 is connected with the motor 35 and also with a circuit wire 70 that is connected with another one of the contact points 49, preferably adjacent to the point to which the wire 63 is connected, so that the wires 63 and 70 may be connected in circuit by the switch bar 57. A circuit wire 71 is connected with the contact device 43 and also with one of the contact points 48. A circuit wire 72 is connected with the wires 69 and 70 and also with one of the contact points 48. A circuit wire 73 is connected with wires 67 and 68 and also with one of the contact points 48, being adjacent to the point 48 to which the wire 63 is connected, so that the wires 63 and 70 may be connected in circuit by the switch bar connector device 54. A circuit wire 74 is connected with the remaining one of the contact points 49 and also with the remaining one of the contact points 48. The contact points 48 to which the wires 71, 72 and 74 are connected are arranged in a group permitting them to be connected in circuit by the switch bar device 55. The contact points 49 to which the wires 66, 67 and 74 are connected are arranged in a group permitting them to be connected in circuit by means of the switch bar device 56.

For supplying the lamp 13 with electric current a feed wire 75 is suitably connected with the wire 74 and extends along the arm 65, and a circuit wire 76 is connected also

with the wire 74 and with a suitably arranged bell or gong 77 which has connection with the return wire 63. A section of the return wire 63 extends along the gate arm 9 from the socket 12 and is suitably connected with the stationary portion of the wire so as to not be disarranged by the swinging movement of the gate arm, being suitably connected with a brush 78 secured to the arm 9 and having contact with a segment 79 concentric to the pivot 8 and having a suitable support 80 on the wall of the housing 5 and in connection with the return wire 63. In practice the wire 75 is similarly connected to a brush 78' having contact with a segment 79', as in Fig. 7. In practice when it is desired to produce intermittent signal lights automatic means is provided to this end, a suitable base 81 preferably being provided so as to support two guides 82 and 83, and a wire 84 is secured to the guide 83 and suitably connected with the wire 75, a coil 85 of suitable structure or composition being connected with the wire 84 and having a rod 86 connected thereto that is movably guided by the guide 82 and has a contact crook 87 thereon normally in engagement with a stud 88 supported by the base 81 and having a feed wire section 75' connected thereto, the section being connected with the socket 12, the structure constituting an automatic circuit breaker operated to break the circuit between the crook 87 and the stud 88 when the coil 85 becomes heated and longitudinally extended, the circuit being re-established when the coil becomes cool.

The circuit connectors indicated generally by the letters A, A' and B, B' are alike but differently arranged along the railway track to obtain the required results in controlling the safety gates by means of the moving trains. Each circuit connector comprises a cylinder 89 having electrical insulating lining 90 and suitable heads inclosing an insulating block 91 supporting contact points 92 and 93 to which the wires 62 and 64 are respectively connected in the two outlying cylinders, the wires 62 and 65 being similarly arranged in the remaining two cylinders. The cylinders are suitably anchored stationarily and are provided on their ends with packing boxes 94 and 94', and the wires in practice are inclosed in a conduit 95 extending through the packing box 94. A rod or plunger 96 is arranged so as to extend through the packing box 94' into the cylinder and has an electrical circuit connector 97 on its end and also a shoulder 98 on which a coil spring 99 is seated under compression and against the connector 97 which is to be moved to the contact points 92 and 93 to connect the circuit when required. The rod 96 has an upwardly extending lug 100 thereon for operation and control of the rod, and a spring 101 connect-

ed to a suitable anchor 102 is connected to the lug to draw the lug towards one of the track rails 2 and break the circuit. A suitable pivot block 103 is provided with a suitable pivot stud 104 and thereby pivotally connected to the web of the rail 2 to support an operating bar C for the circuit connector A and a similar bar D' for the circuit connector B', and similarly to the rail 3 to support a reversely arranged but similar operating bar D for the circuit connector B and a bar C' for the circuit connector A'. The pivot block has a downward extending pivot 105 which may be inclined in operation. Each operating bar comprises a base portion 106 that is connected to the pivot 105, an inclined portion 107 extending from the base and a horizontal portion 108 extending from the inclined portion, the horizontal portion having a relatively obtuse angled portion 108' that extends away from the ball of the rail while the portion 108 is held against the ball by means of the lug 100, which is in contact therewith and drawn thereto by the spring 101. The operating bar has a loop 109 on its side that embraces the lug 100 to maintain the proper relation of the parts. A coil spring 110 is suitably anchored at one end, as to one of the cross-ties and is connected to the pivot 105 which operates as a lever arm to draw the block 103 against a stop pin 111 secured to the track rail, when the horizontal portion 108 of the operating bar is on a level with the top of the track rail.

The equivalent of a locomotive, motor car or other car is represented by a truck having wheels 112 and 113 on the track rails respectively, it being designed that the leading wheels of each car or train shall operate the operating bars when approaching a crossing.

It will be understood that when a crossing is equipped with a plurality of safety gates the operating and controlling appliances for the different gates will be properly supplied with electrical circuits connected with those above described which may be readily supplied by the electrician. Also, various modifications in structural details may be made as may be obvious for the protection of the various parts or elements of the structure. As an instance, the controlling bars may be variously guided to guard against derangement thereof in operation, minor mechanical details within the knowledge of mechanics having been omitted from the structural details of the invention.

In some cases good results may be obtained with a closed circuit electrical system instead of the open circuit system illustrated, and the relays 36 and 37 may be closed by current and opened by springs or may be

closed by springs and opened by current. Also, it may be an advantage to equip the relays with secondary contacts for interlocking and actuating trouble alarms, closing the gate in case of failure of apparatus to operate.

In practical use, as the arm 9 descends the lug 58 is drawn up and engages the switch bar 52 so as to make the proper electrical circuits required to reverse the movement of the arm 9, the switch bar 53 being at the same time carried away from contact points 49. The reverse action occurs when the arm is moved upward to vertical position, the lug causing reverse movement of the switch arms so that they shall be set as in Fig. 9 ready to conduct current for reversing the motor to lower the gate arm. When a train or car approaches as from the left side in Figs. 1 and 2 the wheel 112 engages the angular portion 108' of the operating bar C and forces the bar away from the track rail, resulting in the switch bar 97 being brought into contact with the contact points 92 and 93 and electrically connecting the wires 62 and 64, so that the current shall flow through the wires 62, 64, relay 36 and wire 63, the current energizing relay 36 which causes connection of the contacts 40 and 41 and permits current through the motor from the battery through wires 62, 66, 67, 68, 69, 70 and 63 to the battery, this current energizing the motor to enable it to operate the wheel 29 whereby to lower or close the gate. The time interval in which the contacts 40 and 41 are closed being sufficient for full operation of the gate, the motor continues to operate until the reversing switch is tripped by the lug 58 and the motor current becomes interrupted. The relay 36 is then slowly released by its dash pot. As the train passes on beyond the crossing the wheel 112 operates the bar D' and causes the switch closer B' to act to connect the circuit wires 62 and 65 and complete the electrical circuit through the relay 37 and through the wires 62, 65, relay coil, and wire 63 to the battery, the resulting current energizing the relay 37 which causes the contacts 42 and 43 to be connected and setting up current through the motor by way of the wires 62, 71, 72, 69, the motor, wires 68, 73, 63 and the battery; the current energizing the motor a sufficient length of time so as to operate the wheel 29 in the opposite direction to cause the gate to be opened or elevated. The relay 37 being suitably timed to properly hold the contacts 42 and 43 closed, the motor continues to operate until the reversing switch is tripped by the lug 58 and the motor current becomes interrupted. The relay 37 becomes released by its dash pot. When the relay 36 is energized the bell and the lamp are put in action by a current from the battery, the wires 62, 66, 74, 75, bell, 130

63, and for the lamp through wires 62, 66, 74, 76, 63. Similar operations result when the train runs from right to left and first operates the operating bar C' to close the gate and afterwards operates the controlling bar D to cause the gate to be opened. In case a locomotive or motor car passes and operates the operating bar C, resulting in the gate being closed, and stops after passing the bar D, the gate will be again opened when the car moves away from the crossing and operates the operating bar D. When a train approaches the crossing the wheel flanges will pass over the inclined portion 107 of the operating bar D and depress the bar, and likewise the bar C will be depressed when the train moves away from the crossing. When the operating bars are depressed no operation of the electrical switch or circuit closer occurs.

Having thus described the invention, what is claimed as new is:

1. A railway crossing gate including a movably supported gate, an electrical power device provided with mechanical connections to operate the gate, an electrical circuit for the power device provided with a current-reversing switch, a trip device carried synchronously with the mechanical connections to operate the switch synchronously with the gate, two relays to close or open the circuit on opposite sides respectively of the switch, and a plurality of circuit closers for the relays.
2. A railway crossing gate including a movably supported gate, a supported electrical power device provided with mechanical connections to operate and control the gate, an electrical circuit for the power device provided with a controllable current-reversing switch, a trip device carried synchronously with the mechanical connections to operate the switch synchronously with the gate, a plurality of circuit closers, and two relays to close or open the circuit on opposite sides respectively of the switch to control current for the power device, the relays having different energizing circuits controlled by the different circuit closers.
3. A railway crossing gate including a movably supported gate, a supported electrical reversible power device, mechanical means co-operating with the power device and the gate to operate and control the gate, two electrical relays, an electrical circuit for the power device provided with a current-reversing switch, the circuit having leads to the electrical relays to close or open the circuit on opposite sides respectively of the switch to control current for the power device, a plurality of controlling stations, and a plurality of circuit closers located at the controlling stations respectively with circuit leads respectively to energize and control the relays respectively.

4. A railway crossing gate including a housing, a gate arm pivotally supported by the housing, an electrical power device supported in the housing and having mechanical connections to operate and control the gate arm, an electrical circuit for the power device provided with a current-reversing switch, a trip device carried by the mechanical connections to operate the switch, two relays to close or open the circuit on opposite sides respectively of the switch to control current for the power device, and two circuit closers for the relays respectively and provided with reversely arranged operating bars respectively.

5. A railway crossing gate including a pivotally-supported gate arm, an electrical power device having mechanical connections to move the arm alternately in opposite directions, two circuit closers provided respectively with relatively reversed operating bars, a controllable electrical reversing and cut-out switch, circuit wires for the power device to be connected or disconnected by the switch to conduct current alternately in opposite directions through the power device, a trip device carried by the mechanical connections to operate the switch synchronously with the gate arm, and two electrical relays to control the opening and closing of the circuit on opposite sides respectively of the switch, the relays having different energizing circuits controlled by the circuit closers respectively.

6. A railway crossing gate including a pivotally-supported gate arm, an electrical power device having mechanical connections to move the arm alternately in opposite directions, a controllable electrical reversing and cut-out switch, circuit wires for the power device to be connected or disconnected by the switch to conduct current alternately in opposite directions through the power device, a trip device carried by the mechanical connections to operate the switch synchronously with the gate arm, two outlying circuit closers provided respectively with relatively reversed operating bars, two inner circuit closers provided respectively with relatively reversed operating bars, an electrical relay to control the opening and closing of the circuit wires on one side of the switch and having an energizing circuit to be controlled alternately by the outlying circuit closers, and an electrical relay to control the opening and closing of the circuit wires on the opposite side of the switch and having an energizing circuit to be controlled alternately by the inner circuit closers.

7. In a crossing gate, the combination with track rails, a housing, and a gate pivoted to the housing and having a counter weight, of an electrical reversible motor supported in the housing, mechanical means co-operating with the motor and said

- counterweight to operate the gate, a reversing and cut-out switch supported in the housing, a trip device carried by the mechanical means and adapted to operate the switch alternately in opposite directions on alternate reversal of the motor, circuit wires for the motor controlled for direction of current flow by the switch, the wires extending to different controlling stations, a plurality of mechanically controlled circuit closers located in proximity to the track rails and having devices to open or close the circuits with the wires, and a plurality of operating bars pivotally supported between the track rails adjacent thereto and movable to or from the rails, said bars having operating connection with the circuit closers respectively and being movable idly downward.
- 20 8. In a railway crossing gate, the combination with a railway track, and a crossing, of a gate movably supported in proximity to the track to close or open the crossing, an electrical power device having mechanical
- connections to move and control the gate, an electrical circuit for the power device provided with a current-reversing switch, the circuit having leads to two stations on one side and two stations on the opposite side of the crossing differently distant therefrom, two electrical relays to close or open the circuit on opposite sides respectively of the switch to control current for the power device, and two circuit closers on each side of the crossing at the two stations respectively to connect the two circuit leads respectively to control the relays respectively, the two circuit closers having reversely operated controlling devices arranged in proximity to the track to effect a closing and also a subsequent opening of the gate by a train on one side of the crossing.

In testimony whereof, I affix my signature in presence of two witnesses.

HOWARD C. CARMICHAEL.
